CLAIM

The ornamental design for a combination of protective casing and stand for portable handheld electronic device, as shown and described.

DESCRIPTION

FIG. 1 is a perspective view of the combination of protective casing and stand for portable handheld electronic device in an opened state;

FIG. 2 is a top plan view thereof;

FIG. 3 is a left view thereof;

FIG. 4 is a bottom plan view thereof;

FIG. 5 is a right view thereof;

FIG. 6 is a rear view thereof;

FIG. 7 is a front view thereof;

FIG. 8 is a perspective view of the combination of protective casing and stand for portable handheld electronic device in a closed state;

FIG. 9 is a top plan view thereof;

FIG. 10 is a left view thereof;

FIG. 11 is a bottom plan view thereof;

FIG. 12 is right view thereof;

FIG. 13 is rear view thereof;

FIG. 14 is front view thereof;

FIG. 15 is a reference drawing illustrating insertion of an electronic device into the combination of protective casing and stand for portable handheld electronic device; and,

FIG. 16 is a reference drawing illustrating an operational state in which the combination of protective casing and stand for portable handheld electronic device is used as a stand.

The electronic device shown in broken lines forms no part of the claimed design.
